UNITED STATES PATENT OFFICE.

HERON H. HAWKES, JR., OF DULUTH, MINNESOTA.

SUPPORT.

1,332,834.

Specification of Letters Patent.

Patented Mar. 2, 1920.

Application filed July 15, 1919. Serial No. 310,898.

To all whom it may concern:

Be it known that I, THERON H. HAWKES, Jr., a citizen of the United States, residing at Duluth, in the county of St. Louis and 5 State of Minnesota, have invented new and useful Improvements in Supports, of which the following is a specification.

This invention relates to means for supporting covers of cabinets in open position, 10 and the principal object of the invention is to provide means whereby the support will be released, so that the cover may be closed by a movement of the cover.

Another object of the invention is to provide 15 means whereby the opening movement of the cover will set the parts to hold the cover in open position and a further movement of the cover will move the parts to permit the cover to be closed.

20 The invention also consists in certain other features of construction and in the combination and arrangement of the several parts, to be hereinafter fully described, illustrated in the accompanying drawings and 25 specifically pointed out in the appended claims.

In describing my invention in detail, reference will be had to the accompanying drawings wherein like characters denote like 30 or corresponding parts throughout the several views, and in which:—

Figure 1 is a view of a phonographic cabinet supplied with my invention;

Fig. 2 is an enlarged detailed view showing 35 the parts in position for supporting the cover in open position;

Fig. 3 is a like view with the parts in another position;

Fig. 4 is a sectional view of the supporting 40 plate and some of the attached parts;

Fig. 5 is a view of a slightly different arrangement of the parts;

Fig. 6 is a view of the device applied to a cabinet which has its door in one side 45 thereof.

In these views 1 indicates the cabinet and 2 the cover thereof which is hinged to the top edge of the cabinet in the ordinary manner. A supporting arm 3 is pivoted at its 50 upper end to the cover 2 by the pin 4. A plate 5 is secured to the inner side of the upper portion of the cabinet by means of screws or the like and this plate is provided with a flange 6 at its upper edge in which is 55 a slot 7 through which the arm 3 passes. This arm is provided with a stop projection

8 to limit the upward movement of the cover as this stop will strike the flange and thus prevent further movement of the arm. The arm is provided with a recess 9 adjacent its 60 free end which is provided with a curved bottom wall with the ends cut so as to provide the catches 10 and 11. The plate carries a guiding arm 12 which extends over the arm 3 for guiding the same in its movement. A 65 disk 13 is pivoted to the plate by means of the screw 14 and said disk has its periphery provided with a number of groups of notches, as shown. Each group comprises a pair of notches of substantially V-shape, 70 as shown at 15 and 15' and a third notch 16 which extends in a different direction to the other two notches. This notch 16 is adapted to be engaged by the upper catch 11 to support the cover in open position while the 75 other two notches are adapted to be engaged by the catch 10 at the lower end of the arm for rotating the disk. These notches 15 and 15' are also adapted to be engaged by a pawl 17 pivoted to the plate and yieldingly held 80 against the edge of the disk by a spring 18 located on a guiding arm 19 connected with the plate. This pawl will prevent the disk from being moved in a clockwise direction but will permit it to move in the reverse 85 direction. A spring 20 carried by the cover 2 engages the supporting arm 3 to cause the catches 10 and 11 to engage with the notches of the wheel or disk.

It will thus be seen that when the cover is 90 raised until the stop 8 strikes the flange on the supporting plate the catch 10 will engage the notch 15 and cause the disk to turn until the notch 15 will occupy the position of the notch 15' and the pawl will engage with the 95 next notch of the second group of notches. The first group of notches shown at the bottom of the wheel will advance into a position where the middle notch may be engaged by the catch 10 on the next upward movement 100 of the same. The cover may then be closed as the notch 16 will be moved to a position where it cannot be engaged by the catch 11 so that said catch will simply slide over the periphery of the disk and the parts may 105 occupy their lowered position. The disk is prevented from being rotated by the pawl. When the cover is raised again, the catch 10 will engage the middle notch of the next group so as to place the stop notch 16 of this 110 group in a position to receive the catch 11 when the cover is partly lowered again.

It will, of course, be understood that the notches are arranged so that this operation may be carried out indefinitely. By raising the cover as far as it will go and then partly lowering the same, the catch 11 will engage the stop notch and the cover will be held in open position. When the cover is to be closed it is first raised again to its full open position so as to move the stop notch out of 10 engaging position and thus the cover may be lowered.

In the modification shown in Fig. 5, the arm 3' is placed on the opposite side of the disk and a spring 3^x is provided for holding 15 the arm against the disk. In other respects this form of invention is similar to that just described.

Fig. 6 shows the invention applied to a cabinet 1' which has its opening located in 20 one side thereof so that the door or cover 2' swings outwardly and upwardly. The various parts of the invention in this case are arranged substantially as first described.

While I have shown and described the device as applied to cabinet phonographs, it 25 will, of course, be understood that it may be applied to cabinets used for other purposes.

What I claim is:—

1. In combination with a cabinet and its 30 cover, a supporting arm for the cover having one end pivoted thereto, catches adjacent the other end of said arm, a disk carried by the cabinet, stop means on the disk for engaging one of the catches for holding the 35 arm in position with the cover open and means on the disk operated by the other catch for moving said stop means into and out of operative position.

2. In combination with a cabinet and its 40 cover, an arm pivoted to the cover and having a pair of catches thereon oppositely arranged, a notched disk on the cabinet having the notches therein arranged in groups, each group consisting of a pair of notches spaced 45 apart and extending in the same direction

and a third notch extending in another direction and forming a stop notch, the pair of notches engaging with one catch on the arm for causing the disk to rotate and the stop notch engaging with the other catch to hold the arm in supporting position and a pawl engaging with some of said notches for preventing the disk from rotating in the opposite direction.

3. In combination with a cabinet and its cover, an arm having one end pivoted to the cover, a plate carried by the cabinet and having a slotted flange thereon through which the arm passes, a stop on the arm for engaging the flange to limit the upward movement of the cover, upper and lower catches on the said arm, a disk carried by the plate, stop means on the disk for engaging the upper catch to hold the cover in partly raised position and other means on the disk adapted to 65 be engaged by the lower catch when the cover is raised to rotate the disk to move the stop means into and out of operative position.

4. In combination with a cabinet and its cover, an arm having one end connected with 70 the cover, a plate carried by the cabinet, a flange on the upper edge of the plate having a slot therein through which the arm passes, upper and lower catches on one edge of said arm, a stop on the other edge for limiting 75 the upward movement of the cover by engaging with the flange, a guide arm on the plate for said supporting arm, a disk pivoted to the plate and having groups of notches in its periphery, some of said notches being arranged to be engaged by the lower catch when the arm is raised to rotate the disk in one direction and one of the notches of each group being adapted to be engaged by the upper catch for holding the arm against downward movement and a pawl engaging some of said notches for preventing rotation of the disk in the opposite direction.

In testimony whereof I affix my signature.

HERON H. HAWKES, JR.
